CLAIM

The ornamental design for a intercommunication device, as shown and described.

DESCRIPTION

FIG. 1 is a front, left, top perspective view of an intercommunication device showing our new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines in the drawings illustrate portions of the intercommunication device that form no part of the claimed design.

1 Claim, 5 Drawing Sheets
